UNITED STATES PATENT OFFICE.

CHARLES H. HISER, OF SPRINGFIELD, OHIO, ASSIGNOR TO THE SPRINGFIELD METAL-LIC CASKET COMPANY, OF SPRINGFIELD, OHIO, A CORPORATION OF OHIO.

DESIGN FOR A HANDLE FOR A BURIAL CASKET.

Application filed October 24, 1925. Serial No. 15,240. Term of patent 7 years.

To all whom it may concern:

Be it known that I, CHARLES H. HISER, a citizen of the United States, residing at Springfield, in the county of Clark and State of Ohio, have invented a new, original, and ornamental Design for a Handle for a Burial Casket, of which the following is a specification, reference being had to the drawing, forming part thereof.

The figure is a plan view of a handle for burial caskets showing my new design.

I claim:

The ornamental design for a handle for a burial casket as shown.

CHARLES H. HISER.
